(57) **CLAIM**

The ornamental design for a hand held hair appliance brush attachment, as shown and described.

DESCRIPTION

FIG. 1 is a perspective view of a hand held hair appliance brush attachment showing our new design;
FIG. 2 is a front elevation view of FIG. 1;
FIG. 3 is a rear elevation view of FIG. 1;
FIG. 4 is a left side elevation view of FIG. 1;
FIG. 5 is a right side elevation view of FIG. 1;
FIG. 6 is a top plan view of FIG. 1;
FIG. 7 is a bottom plan view of FIG. 1;
FIG. 8 is a perspective view of FIG. 1; and,
FIG. 9 is a perspective view of FIG. 1.

The broken lines in the drawings depict portions of the hand held hair appliance brush attachment that form no part of the claimed design.
